SURFACE PROJECTILE

Filed April 21, 1928

FIG. 1.

FIG. 2.

FIG. 3.

INVENTOR

Elbert O. Brower

UNITED STATES PATENT OFFICE.

ELBERT O. BROWER, OF HUNTINGTON, NEW YORK.

SURFACE PROJECTILE.

Application filed April 21, 1928. Serial No. 271,788.

This invention relates to amusement devices, and more particularly to games or puzzles in which one or more players or operators cause one or more traveling elements 5 to move upon a game board or similar element by tilting or otherwise manipulating the latter.

This invention, and the invention described and claimed in my United States patent application, Serial No. 265,418, filed March 28, 1928, may be regarded as specific forms of a generic invention having for its general object the production of traveling elements having novel characteristics of behavior which 15 will be interesting and entertaining. A particular object of the present invention is to provide a traveling element which is very inexpensive to manufacture. Another particular object of the present invention is to 20 provide a traveling element which readily can be made of very small size, and is adapted to operate satisfactorily upon a floor element of relatively small area.

In the drawing, Fig. 1 shows one form of 25 my invention, being partly in plan view and partly in cross-section.

Figure 2 shows a similar view of a different form.

Figure 3 shows a similar view of still another form.

In Fig. 1, 1 is a simple cylinder, which may be made of brass, and which may be plated with nickel or otherwise if desired. In the middle of the cylinder 1 is cut an annular groove 2, which forms a seat for the ring 3 which may be of rubber. A particular function of the ring 3 is to provide near the middle of the cylinder, a relatively sharp ridge or tire having a perimeter greater than the 35 perimeter of either end of the cylinder, and adapted to permit the device to roll upon a floor element 4 which is approximately level while having contact therewith at a portion of this large perimeter and at either end of 40 the cylinder 1.

Fig. 2 shows an embodiment which may be of lead, and which may be cast in the form shown, which is that of two equal frusta of cones of revolution placed with their larger 45 bases in coincidence.

Fig. 3 shows a modification of the embodiment of Fig. 2; the form being altered in an attempt to simulate the general form of a tadpole.

The center of gravity of the embodiment of Fig. 2 is coincident with the common cen-

ter of the larger bases of the frusta; and in any embodiment, the center of gravity of the device should be not too far from the analogous point, that is to say, the center of that lateral section which has the greatest diameter. In a case where the ends of the device are of different form, as in the embodiment of Fig. 3, it may be possible to effect a proper balance by modifying the exterior form only; and in some other cases a proper balance may be obtained less simply by drilling holes into one portion of the device in order to make this portion of lesser weight.

It is plain that the embodiment of Fig. 2 will be in stable equilibrium, as regards the inclination of its axis, while it is resting upon a level floor element as indicated in the figure. When this embodiment rolls upon a flat floor element, its path is substantially circular, and the device is disposed to remain in this circular path, so long as its velocity is not too great, if the floor element is not tilted or disturbed too much; however such motion in a curved path involves a centrifugal force which tends to tip the device so as to bring its elevated end down to contact with the floor element. If the centrifugal force prevails thus, the device continues to roll, but about a new center, and with a new centrifugal force which tends to effect another such tipping action. The greater the velocity of the device, the shorter the interval between successive tipping actions, and the more nearly does the path approach a straight line.

If the edge 6, Fig. 2, were rounded off too much, the device would be too much inclined to follow such an approximately straight path.

The angle of the cones may be made as I have shown it in the figure. If the angle is made too much smaller, the behavior of the device is less interesting. If the angle is made too much greater, too high a velocity of the device, or too violent a disturbance of the floor element, is required to effect the tipping action.

When a plurality of the devices are used at the same time upon one floor element, and it is desired to move each device to some particular station thereon, one device may be manœuvred to its station while ignoring the actions of the others, and then it becomes a problem how to manipulate the floor element so as to cause another device to travel as desired without disturbing the first enough to make it tip. If the floor element is given

a sudden limited movement of simple translation, two devices which were at rest thereon, and differently oriented, may be affected very differently; for example, one may be caused to tip immediately without previously rolling, and the other may be started rolling in its path without being caused to leave the same. If the floor element is given a movement of rotation about a center which is near one device thereon, this one may be affected much less than another device which is located at a distance from said center.

What I claim is:—

1. A surface projectile consisting of an elongated body of greatest diameter near its center of gravity; the form of this portion of said body being abruptly tapered longitudinally in both directions from the circumference of said diameter.
2. In an amusement device, an elongated body having a sharp ridge on its periphery intermediate its ends, in combination with a

movable floor element for said body to roll and move upon; the peripheries of said ridge and of said ends being approximately circular, and the perimeter of said ridge being greater than the perimeter of either of said ends.

3. A surface projectile having substantially the form of two frusta of cones placed with their larger bases in coincidence.

4. A surface projectile having substantially the form of two frusta of cones of revolution placed with their larger bases in coincidence.

5. A surface projectile or game piece having substantially the form of two frusta of cones of revolution placed with their larger bases in coincidence; the angles of said cones being equal.

Signed by me at Huntington, N. Y., this twentieth day of April, 1928.

ELBERT O. BROWER.
